CHIP-REMOVING MECHANISM.

Application filed February 29, 1924. Serial No. 696,066.

This invention relates to means for and method of handling chips which are formed during the production of foldable blanks to form containers. One application of the invention is herein shown in connection with envelope blanks.

An object of the invention is to provide a chip removing device comprising a chip engaging element which when actuated moves in an orbit to one side of its support and in a plane extending transversely of the material acted upon to remove the chips.

Another object of the invention is to deposit the removed chips on a conveying device by which they are carried to a suitable container into which they are discharged.

Another object of the invention is to accumulate the chips on the conveying device so that they may be discharged therefrom in packs to prevent their being blown about and becoming entangled in the machinery.

A feature of the invention relates to means to fold the chips so that they may be so accumulated or stacked by placing them one within the other, i. e., nesting them, on the conveying device, the speed of the conveying device being slow as compared with the movement of the chip engaging element to thus assist in accumulating the chips.

Another feature of the invention relates to means to adjust the throw of the chip engaging element to thus vary its extent of overlap from the edge of the material for chips of different depths.

Still another feature of the invention relates to adjustable means to vary the movement of the chip engaging element towards the conveying device.

A further feature relates to means to vary the length of the chip engaging element according to the location of the material.

The above and certain other objects of the invention will now be described with particular reference to a preferred form of embodiment of the invention illustrated in the accompanying drawings, in which:

Figure 1 is a vertical section of the mechanism taken on the line 1—1 of Figure 3;

Figure 2 is a sectional top plan view showing the fulcrum of the chip engaging element and its adjustment.

Figure 3 is a top plan view of the parts shown in Figure 1;

Figure 4 is a detail top plan view showing

two chip removing devices, one at each edge 55 of the material;

Figure 5 is a vertical section of the mechanism taken on the line 5—5 of Figure 1;

Figure 6 is an enlarged view illustrating the accumulation of the chips between the 60 belts of the conveying device;

Figure 7 is a detail sectional view showing the connection between the chip engaging element and its actuating means.

In the present application of our invention a continuous web 10, Figures 3 and 4, of envelope blanks 11, having chips 12 in its edges, is advanced by feed rollers 13 and 14, Figure 5, over a table 15, secured to a main frame 16. In removing the chips from the web there is utilized a device which comprises a chip engaging element having a blade 17, normally disposed above the web 10 as in Figure 1. Said blade is actuatable as hereinafter described, and is so timed with reference to the feed of the web 10 that it is depressed every time a chip is brought into its path. The depression of the blade removes the chip 12 from the blank and folds the chip by passing it thru a slot 18 in the table 15, to dispose of the chips in a manner hereinafter described.

The actuating means for the chip removing blade 12 comprises a shaft 19, which rotates in the main frame 11, it being driven in any suitable manner. Said shaft has secured thereto a bevel gear 20, meshing with a bevel gear 21, to rotate the latter in a clockwise direction, Figure 1. The bevel gear 21 rotates on a stub shaft 22, secured to a bracket 23 of the main frame 10, Figure 3, and is connected by a sleeve 24 to a spur gear 25, meshing with a gear 26 to drive the latter in a counter clockwise direction, the gear 26 being revolvably supported on a headed stud 27, Figure 3, secured to an extension 28 of the bracket 23 by a nut 29. The gear 26 has connected thereto a crank arm 30, also mounted on the stud 27, by means of a hub 31, and secured to the side of the gear 26 by a screw 32 which extends thru a slot 33 in an extension 34 on said hub and on the side opposite to the crank arm 30, the screw 32 being threaded into the gear 26. Thus it will be understood that when the gear 26 is rotated the crank arm 30 rotates with it.

The chip engaging blade 17 is provided with a stem 35 which is slidingly supported

in a bearing block 36 fulcrumed on a pin 37 of a disc 38 secured by a nut 40 to a bracket 39 on the main frame 16, the nut 40 being threaded on a binding post 41, Figure 2, extending from the opposite side of the disc 38 and extending thru the bracket 39. The stem 35 of the blade is connected near its end to the crank arm by a coupling 42. The blade stem 35 extends thru a hole in a block 44 of said coupling 42. To fasten the stem to the coupling block there is provided a bolt 45 in a hole 46 and extending at right angles to the stem 35. The bolt 45 has a segmental groove or kerf 47 thru which the stem 35 passes so as to be partially embraced by said bolt, the latter being provided with a nut 48 at one end, which when drawn up binds the bolt 45 against the stem 35 to securely hold the latter in place on the coupling block 44.

The coupling block 44 is supported by means of a wrist pin 49 secured to the crank arm 30, the wrist pin having for this purpose a rectangular head 50 received in a slot 51. The head 50 is provided at one end with a circular flange 52 to bear against one side of the crank arm 30, the other end of said head having a binding post 53 with a nut 54 threaded thereon to bear against the other side of the crank arm to tighten up and to bind the wrist pin in place. The wrist pin 49 has a nut 55 at its end to keep the coupling block 44 on said pin.

From the foregoing it will be understood that as the gear 26 rotates it causes the wrist pin 49, which is the effective point of connection with the blade stem of the chip engaging element to travel in a circle, thus vibrating the chip engaging element (which in effect is a lever moved about the stud or fulcrum 37) and also moving said element back and forth in the bearing block or sleeve 36. This combined vibratory and reciprocatory movement of the chip engaging element causes its blade 17 to travel in an orbit comprising four stages, substantially as indicated at A, B, C, D, Figure 1. During the first stage of its movement the blade moves from A to B crosswise of the material or web 10 to remove the chip by drawing it thru the slot 18, in the table. This movement is the working stroke and is performed at relatively fast speed because the leverage of the chip removing element between the fulcrum 37 and the point of connection 49 is comparatively short. During the second stage of its movement, namely from B to C, the blade moves beneath the web and outward beyond the edge preliminary to moving past the edge from C to D, which is the third stage of the movement. The blade then moves inwardly over the material from D to A, this being the fourth stage of its movement, thus completing one cycle of operation. The working stroke of

the blade is completed slightly beyond the point B from which the return stroke of the blade and also its withdrawal from the removed chip, begins. It will be understood that the blade move substantially parallel to the web from B to C and from D to A.

In addition to the chip removing device arranged at the left-hand edge of the web 10 there is another one arranged at the right-hand edge as shown in Figure 4. These two devices are oppositely disposed and driven in opposite directions and they are so timed with respect to each other and with respect to the web to move downwardly together every time a pair of chips is brought into their paths.

It will be understood that webs of various widths may be employed in the device of the present invention. For this purpose each chip removing element is adjustable in the direction of its length and with reference to the location of the edge of web. To this end the length of each chip engaging element may be varied to cause it to extend inwardly over the web more or less as desired. To vary the length of said element the nut 48 is loosened, thus relieving the clamping effect of the bolt 45 on the stem 35 of the chip engaging element, after which the latter may be shifted back or forth in the coupling block 44 according to the desired length. After adjusting said element it may again be clamped in place on the coupling block by drawing up on the nut 48.

It will further be understood that the depths of the chips, or in other words, the distance that they extend inwardly from the edge of the web, may vary according to the size and character of the envelope blanks. To permit the device to be used for chips of various depths, the coupling block 44 is adjustable on the crank arm to increase or decrease the throw of said chip removing element.

The adjustment of the point of connection is effected by loosening the nut 54 so that the wrist pin may be moved toward or away from shaft 27 according to the extent of throw desired. After adjustment, the wrist pin is fixed in place by the nut 54. It will be understood that as the gear 26 rotates the wrist pin 49 revolves freely within the coupling block 44, said block remaining always at right angles to the stem 35 of the chip removing element.

Means comprising a conveying device 56 are provided to receive the chips from the blade 17 and carry them to a container 57 into which they are discharged. The conveying device includes two belts 58 and 59, the belt 58 running over rollers or pulleys 60 and 61 on shafts 62 and 63, respectively, and the belt 59 running over pulleys 64 and 65 on shafts 66 and 67 respectively. The

conveyer belts are so placed as to have two of their strands face to face and close to each other to form what may be termed a guideway, 68, extending downwardly from the rollers 60 and 64 to the container 57. The blade 17 moves between the rollers 60 and 66 to deposit the chips on the belts 58 and 59 by which they are drawn downwardly and guided to the container.

10 The conveyer belts may be driven in any suitable manner, and preferably at a comparatively slow speed with respect to the vibrations of the chip blade 17 so that the chips are stacked or accumulated between the conveyer belts 58.

15 It will be observed that each chip is folded as it is passed thru the slot 18 of the table 15 and is nested within the precedingly removed chip. The chips are fed out between the pulleys 61 and 62 in a sort of strip which, when it gets heavy enough, breaks to thus discharge the chips in packs into the container 57. Flying about of individual chips is thus prevented.

20 25 The rollers 60 and 64 are separated sufficiently to allow the blade 17 to move downwardly between them to deposit the chips on the belts 58 and 59. The rollers 61 and 65 are placed close enough to cause the belts 30 to bear firmly against each other and thus produce a sharp crease in each chip.

35 The belts 58 and 59 of the conveying device extend under the table 15 to the chip removing device at the other edge of the web 10, so that a single pair of belts may be effective to convey the chips removed by both devices.

40 Means are also provided for each chip removing element to adjust its movement toward the rollers 60 and 64 of the conveying device, to enable it to move sufficiently down between the rollers to properly deposit the chips thereon. Another reason for this adjustment is to cause chips of various widths 45 to be completely drawn thru the table 15 to avoid clogging of the slot 18, it being necessary for the blade 17 to move down further for wide chips than for narrow chips.

50 To adjust the movement of the blade 17 towards the conveying device, the fulcrum pin 37 on which the sleeve 36 is mounted is eccentrically mounted on the disc 38, Figures 1 and 2, so that after the nut 40 has been loosened the disc may be rotated about the axis of the binding post 41 to raise or lower the fulcrum pin 37 and consequently raise or lower the blade 17 by means of the sleeve 36 in which the stem 35 is guided, the chip engaging element being swung during such adjustment about the wrist pin 49.

55 The sleeve is held on the fulcrum pin 37 by a nut 70, and said fulcrum pin is short enough so as not to interfere with the movement of the stem 35 of the blade 17.

60 65 It will be understood that although the in-

vention is illustrated in connection with envelope blanks and these in a continuous web, it may be used in connection with blanks of other kinds of containers and that the blanks may be separated instead of connected in a continuous web.

70 Various other changes and modifications may be made in the illustrated embodiment of the invention, it being our intention to claim the same as broadly as the prior state of the art will permit.

What we claim is:

1. A chip removing device comprising a chip engaging element, and operating means for passing said element thru a cycle of 80 movement intersecting the material acted upon, said means being arranged to cause accelerated movement of said element at the point at which the material is intersected by the element.

85 2. A chip removing device comprising a blade and means for impressing longitudinal and pivotal movements on said blade, said means comprising mechanism for causing the pivotal movement in one direction to be 90 at a greater rate of speed than the pivotal movement in the reverse direction.

95 3. In a device for removing chips from a sheet of material, a blade, and means for passing said blade transversely thru said sheet and for thereupon withdrawing said blade in a direction substantially parallel to the sheet.

100 4. In a device for removing chips from a sheet of material, a blade, and means for passing said blade thru a repeated cycle of movements with reference to the sheet, said cycle comprising a first movement substantially transverse to the sheet to remove the chip therefrom, a second movement substantially parallel to the sheet to withdraw the blade from under the sheet, a third movement substantially transversely to the sheet to return the blade to an elevation above the sheet, and a fourth movement substantially parallel to the sheet to return the blade into operative position.

105 5. A chip removing device comprising a lever, a fulcrum for said lever, a chip engaging member at one end of said lever, means engaging the other end of said lever to vibrate the lever about its pivot, and means to vary the effective fulcrum relatively to the lever.

110 6. A chip removing device comprising a lever, a fulcrum for said lever, a chip engaging member at one end of said lever, a shaft, an arm on said shaft, and means connecting said arm and said lever so that the arm, when rotated with said shaft will vibrate said lever about its fulcrum and reciprocate it in the direction of its length.

115 7. A chip removing device comprising a chip engaging element, operating means for passing said element thru a cycle of move-

ment intersecting the material acted upon, said means being arranged to cause accelerated movement of said element at the point at which the material is intersected by the 5 element, and a table over which the material is fed, said table having a slot thru which the chips are passed by said element.

8. A chip removing device comprising a chip engaging element, operating means for 10 passing said element thru a cycle of movement intersecting the material acted upon, said means being arranged to cause accelerated movement of said element at the point at which the material is intersected by the 15 element, and a table over which the material is fed, said table having a slot thru which the chips are passed by said blade and adjustable means to vary the extent of movement of said blade thru said table.

20 9. A chip removing device comprising a blade and means for impressing longitudinal and pivotal movements on said blade, and adjustable means to vary the line of engagement of said blade with the material.

25 10. A chip removing device comprising a blade and means for impressing longitudinal and pivotal movements on said blade, adjustable means to vary the line of engagement of said blade with the material, and means to vary the extent of longitudinal movement of said blade.

30 11. A chip removing device comprising a chip engaging element, operating means for 35 passing said element thru a cycle of movement intersecting the material acted upon, said means being arranged to cause accelerated movement of said element at the point at which the material is intersected by the 40 element, a table over which the material is fed, said table having a slot thru which the chips are passed by said blade, and adjustable means comprising an eccentrically mounted fulcrum for said blade.

45 12. A chip removing device comprising a chip engaging element, means for actuating said element thru a cycle of movement intersecting the material acted upon, said element being normally disposed at one side 50 of the material to be acted upon, and an opposing element at the opposite side of the material, said opposing element having a slot thru which the chip engaging element passes to remove the chip from the material.

55 13. A chip removing device comprising a chip engaging element, means for actuating said element thru a cycle of movement intersecting the material acted upon, said element being normally disposed at one side of the material to be acted upon, an opposing element at the opposite side of the material, said opposing element having a slot thru which the chip engaging element passes to remove the chip from the material, and

means to vary the extent of movement of said chip engaging element thru said slot.

14. A chip removing device comprising a chip engaging element, means for actuating said element thru a cycle of movement 70 intersecting the material acted upon, said element being normally disposed at one side of the material to be acted upon, an opposing element at the opposite side of the material, said opposing element having a slot 75 thru which the chip engaging element passes to remove the chip from the material, said chip engaging element having an outward movement to clear the edge of the material, and means to vary the extent of said outward movement.

15. A chip removing device comprising a chip engaging element, and means to actuate said element to first move it towards the material acted upon to remove the chip 85 and then substantially parallel to the plane in which the material lies.

16. A chip removing device comprising a pivoted chip engaging element, and means to actuate said element so that it moves in 90 an orbit to one side of its pivot, the orbit intersecting the material acted upon.

17. A chip removing device comprising a vibrating chip engaging element moving in 95 an orbital path, and actuating means therefor, the orbital path in which the chip engaging element moves intersecting the material to be acted upon at one point and clearing the edge of the material at a point opposite the edge of the material.

100 18. A chip removing device comprising a chip engaging element, a revolvable shaft, a crank arm on said shaft, a connection between said crank arm and said element, a bearing block in which said element may slide back and forth, and a pivotal support for said block, the connection between the crank arm and said element being adjustable to vary the length of the stroke of the latter, and said pivotal support being adjustable to vary the extent of throw of said element thru the material acted upon.

105 19. The combination of a chip removing device, conveyer belts to receive said chips from said device and a container into which 115 said chips are discharged from the receiving device.

20. The combination of a chip removing device arranged to act vertically downward on horizontally disposed material, a device 120 arranged beneath said material to receive the removed chips, and a container arranged under said receiving device into which the chips are discharged.

125 21. The combination of a chip removing device, and a pair of conveyer belts to receive at its one end the removed chips and discharge them at its other end.

22. The combination of a chip removing device, a belt conveyer to receive the chip 130

- at one end from the chip removing device, and means to hold the chips on the conveyer to cause them to travel therewith so that they may be discharged from the conveyer 5 at its other end.
23. The combination of a chip removing device, a belt conveyer to receive the chips at one end from the chip removing device, and a belt to hold the chips on the conveyer 10 belt to cause them to travel therewith, the chips being discharged from said conveyer belt at its other end.
24. The combination of a device to remove chips from a piece of material, and 15 a device to receive the chips as they are removed from the material, the receiving device comprising two oppositely disposed feeding elements.
25. The combination of a device to remove 20 chips from a piece of material, and a device to receive the chips as they are removed from the material, the receiving device comprising two oppositely disposed rotating rollers.
26. The combination of a device to remove 25 chips from a piece of material, and a device to receive the chips as they are removed from the material, the receiving device comprising oppositely disposed rotating rollers 30 and belts running over said rollers.
27. The combination of a device to remove chips from a piece of material, a device to receive the chips as they are removed from the material, the receiving device comprising 35 feeding elements, and a container, said elements being continuous and oppositely disposed so that the chips may be inserted between them and fed thereby to deposit them in said container.
28. The combination of a device to remove 40 chips from a piece of material, and two belts positioned face to face and running over pulleys, said belts being arranged to receive the chips as they are removed from the material and to feed the chips to a suitable 45 location.
29. The combination of a chip removing device, a chip folding device, and means to receive the folded chips to feed them and 50 then discharge them at a suitable location.
30. The combination of a chip removing device, a chip folding device, means to receive the folded chips to discharge them from the machine, said chip removing device comprising a chip engaging element 55 actuatable towards the chip receiving means, and means to adjust the throw of said chip engaging element towards the receiving means.
31. The combination of a chip removing device comprising a chip removing element 60 to act upon the material and remove the chip, a table to support the material, said table having a slot through which the chips 65 are passed by the chip engaging element to fold them, and a conveyer to receive said chips.
32. The combination of a device to remove chips from material acted upon, means to fold said chips, means to nest said chips, and 70 means to discharge the nested chips from the machine.
33. The combination of a device to remove chips from material acted upon, means to temporarily accumulate said chips, and 75 means to discharge said chips in accumulated condition from said machine.
34. The combination of a device to remove chips from the material acted upon, oppositely disposed rollers between which the 80 chips are deposited by said device, and means comprising a guide-way for said chips, said guide-way being associated with said rollers and comprising two walls between which the chips are accumulated so 85 that they may be discharged in accumulated condition from the machine.
35. A chip conveying device comprising two belts so placed as to have two strands running parallel and face to face, and pulleys over which said belts run, the chips being received at one end of the conveying device between the belts and discharged at the other end, the pulleys at the discharging end of said device being staggered to permit contact 90 between the faces of the belts and also permit free passage of the chips between said pulleys.
36. A chip conveying device comprising two belts so placed as to have two strands 95 running parallel and face to face, and pulleys over which said belts run, the chips being received at one end of the conveying device between the belts and discharged at the other end, the belts being slightly separated at the receiving end of the device to enable 100 the insertion of the chip between said belts.
37. A chip conveying device comprising two belts so placed as to have two strands 105 running parallel and face to face, and pulleys over which said belts run, the chips being received at one end of the conveying device between the belts and discharged at the other end, the belts being slightly separated at the receiving end of the device to enable 110 the insertion of the chip between said belts, the pulleys at the discharge end of said device being staggered to permit contact between the belts and also permit free passage 115 of the chips.
38. The combination of a chip removing device, comprising an actuatable chip engaging element, a conveyer to which the chips are passed by the chip engaging element, and means to adjust the movement of said element toward said conveyer. 120
39. The combination of a chip removing device comprising an actuatable chip engaging element, a pair of belts so arranged that the chips may be deposited between them by 125 the 130

chip engaging element to be conveyed away, and means to adjust the movement of said chip engaging element towards the belt.

40. The combination of two chip removing devices disposed at opposite edges of the material to be acted upon, a conveyer device to receive the chips from said removing devices, each chip removing device comprising actuating means, and means for adjusting 10 each chip removing device, to vary its movement toward the conveyer device independently of the other chip removing device.

41. A chip removing device comprising a chip engaging element, means to actuate said element, and means to facilitate an adjustment of the length of said element.

42. A chip removing device comprising a chip engaging element, means to actuate said element, and driving means for said element, 20 and means connecting said element with said driving means, said connecting means comprising means to enable adjustment of the length of said element.

43. A chip removing device comprising a chip engaging element, revolute actuating means, an element connecting said actuating means with said chip engaging element, said connecting element traveling in a circle, means to vary the diameter of said circle to 30 vary the throw of said chip engaging element, and means to enable an adjustment between the connecting element and the chip engaging element to vary the length of the latter.

44. The method of removing chips from sheet material which consists in passing a blade thru the material and folding the chip about the blade, inserting the folded chip between conveyer belts, and withdrawing the blade from said chip in a direction substantially parallel to the fold in the chip.

45. The method of removing a chip from a sheet of material, which consists in passing a blade transversely thru the material and 45 folding the chip about the blade, inserting the folded chip into conveyer mechanisms, and removing the blade in a direction substantially parallel to the sheet.

46. The method of removing a chip from

a sheet of material, which consists in passing 50 a blade transversely thru the sheet and withdrawing the blade substantially parallel to the sheet.

47. The method of handling chips, which consists in removing the chips from the material acted upon, folding them and then discharging them in folded condition.

48. The method of handling chips which consists in removing the chips from the material acted upon, folding them, nesting them 60 and then discharging them.

49. The method of handling chips which consists in removing the chips from the material acted upon, folding them, nesting them, conveying them in nested condition, 65 and then discharging them.

50. The method of handling chips which consists in removing the chips from the material acted upon, folding them, accumulating them in folded condition and then discharging them in packs.

51. The method of handling chips which consists in removing the chips from sheet material, folding the chips and stacking them by slowly feeding them from the place 75 where they are removed from the material.

52. A chip removing device comprising a chip engaging element, means to actuate said element, means to facilitate an adjustment of the length of said element, and a clamp 80 to embrace said element and to enable adjustment of the length of said element.

53. In a machine for making paper articles such as envelopes, the combination with sheet material feeding mechanism of a chip removing device comprising a chip removing element, and means for operating the element, said means being arranged first to move the element transversely through the plane of the material being operated upon, 90 then withdraw the element in the direction of its length beyond the edge of the material, and then to raise and advance the element preparatory to its next chip removing stroke.

In testimony whereof we have affixed our 95 signatures to this specification.

EDWARD FISH.
ABRAHAM NOVICK.
